Patented Nov. 11, 1975

237,612

FISH LURE

James D. Maxwell, Box 649, Vancouver, Wash. 98665

Filed Sept. 7, 1973, Ser. No. 395,373

Term of patent 14 years

Int. Cl. D22—05

U.S. Cl. D22—27

FIG. 1

FIG. 2

FIG. 4

FIG. 3

FIG. 5

FIG. 1 is a side elevational view of a fish lure of the present design;

FIG. 2 is a top plan view, taken on the line 2—2 of FIG. 1;

FIG. 3 is a bottom plan view, taken on the line 3—3 of FIG. 1;

FIG. 4 is an end view, taken on the line 4—4 of FIG. 1; and

FIG. 5 is an end view, taken on the line 5—5 of FIG. 1.

The leader portion of the design has been broken off for convenience of illustration.

I claim:

The ornamental design for a fish lure, as shown.
